UNITED STATES PATENT OFFICE

158,648

METAL STRIP

Alan Caccia, Philadelphia, Pa.

Application January 26, 1949, Serial No. 516

Term of patent 14 years

(Cl. D54—2)

To all whom it may concern:

Be it known that I, Alan Caccia, a citizen of the United States, residing at Philadelphia, in the county of Philadelphia, and State of Pennsylvania, have invented a new, original, and ornamental Design for Metal Strips, of which the following is a specification, reference being had to the accompanying drawing, forming part thereof.

Figure 1 is a front elevation; Figure 2 a top plan view, and Figure 3 an end elevation of a metal strip showing my new design.

I claim:

The ornamental design for a metal strip, as shown.

ALAN CACCIA.
